[57] CLAIM

The ornamental design for a jar stirrer housing, as shown and described.

DESCRIPTION

FIG. 1 is a front perspective view of the jar stirrer housing of the present invention;

FIG. 2 is an end elevation view, the opposite end elevational view being a mirror image;

FIG. 3 is a top elevation view thereof;

FIG. 4 is a bottom elevation view thereof;

FIG. 5 is a front elevation view thereof; and,

FIG. 6 is a back elevation view thereof.

*Fig. 1**Fig. 2**Fig. 3**Fig. 4**Fig. 5**Fig. 6*
